UNITED STATES PATENT OFFICE.

FRED N. CLINE, OF CHICAGO, ILLINOIS.

HORSESHOE.

SPECIFICATION forming part of Letters Patent No. 741,110, dated October 13, 1903.

Application filed December 29, 1902. Serial No. 136,996. (No model.)

To all whom it may concern:

Be it known that I, FRED N. CLINE, a citizen of the United States, residing at Chicago, in the county of Cook and State of Illinois, have invented new and useful Improvements 5 in Horseshoes, of which the following is a specification, reference being had to the accompanying drawings, forming a part thereof.

This invention is designed as an improvement 10 in horseshoes having rubber calks, the specific purpose being to cheapen and increase the efficiency of the construction by which the calks are removable without removing the shoe. It consists in the features 15 of construction set out in the claims.

In the drawings, Figure 1 is a plan of a horseshoe embodying my invention, having one of the heel-calks shown in full and the other with the rubber removed. Fig. 2 is a 20 detail section at the line 2 2 on Fig. 1. Fig. 3 is a section at the line 3 3 on Fig. 2. Fig. 4 is a view similar to Fig. 3, showing a slight modification.

My improved shoe comprises a body forged, 25 pressed, or otherwise produced from suitable metal and having the usual means for securing to the hoof. This body A has a toe-calk 1 of a special form adapted to prevent the calk from becoming engaged in slots or crevices, such as the slots of cable or under- 30 ground electric railways, the calk being formed in the arc of a circle, so that while it is narrow enough at the edge to afford secure grip it has by reason of its curvature 35 too great an extent fore and aft to permit it to enter a narrow slot or crevice.

In each heel of the body A there is formed a socket or pocket 2 for receiving and retaining the removable calks. In the form shown 40 in the principal figures there is provided a lug 3, projecting from the web in the pocket 2 at a point intermediate the rear and forward ends of such pocket.

45 4 is a metal skeleton or gridiron for holding and giving rigidity to the rubber calk, which is molded so as to embed said skeleton, as seen in sectional view of Fig. 2. This skeleton is adapted to fit the pocket 2, and it has a lug 5 projecting alongside the lug 3, 50 the contiguous faces of the two lugs being substantially at right angles to a line extending lengthwise of the pocket from a point

substantially at the middle of the rear end to the foremost extremity. At the middle of the rear end of the pocket there is formed a slight exterior angular recess 6 for the purpose of affording an exterior face parallel with the contiguous faces of the lugs 3 and 5—that is, at right angles to the line of a bolt to be inserted, as hereinafter described. The angular recess described produces a corresponding angular projection or boss 6^a into the pocket, and the skeleton or gridiron 4 has a corresponding angular recess 7 and a corresponding inwardly-protruding boss 8. The lugs 3 and 5 have coinciding apertures 9 and 10 in line with apertures 11 and 12, the former in the boss 6^a and the latter in the boss 8. 15 13 is a bolt or screw which is inserted through the apertures 11, 12, 9, and 10 and immediately penetrates the rubber 14, in which the skeleton or gridiron 4 is embedded. This bolt or screw has a smooth terminal 15, which extends through the apertures 9 and 10 in the lugs 3 and 5, fitting them close enough to prevent looseness or rattling of the parts which are thus held in connection. The aperture 12 in the boss 8 is threaded, and the bolt 13 is correspondingly threaded at 16 over the shoulder next the head, so that when the bolt is inserted it may be screwed into the boss 8, and thereby held. Preferably, but not necessarily, the bolt has a tapered head, and the aperture 11 is exteriorly countersunk to lodge such head, and the thread 16 is preferably formed over the whole of the shoulder up to the head, so that the bolt may be screwed in far enough to clamp the skeleton 4 against the rear wall of the pocket in which it was lodged, and thus more effectually prevent any rattling, which might result if the skeleton were fitted loosely to the pocket. Intermediate the shoulder having the thread 16 and the terminal 15, which engages the apertures in the lugs 3 and 5, I prefer to form this bolt with a spiral fin or thread 17, substantially such as is customary on screws for engaging wood, and for like purpose I give the bolt a slight taper over this portion, which, it will be understood, extends through the rubber and is engaged therewith, being screwed into it as into wood. Preferably in order to steer the bolt directly through the rubber the latter is formed in molding with an aperture in the

right position—that is, in line between the apertures in the boss 8 and lug 3—said aperture, however, being no larger than necessary to accommodate the shank or unreduced portion of the bolt, leaving the rubber for the engagement of the thread or fin when the bolt is screwed into it. As may be understood, the action of a screw cutting its way into rubber in this manner lays the fibers of the rubber in the direction in which they are drawn by the inward-rotation progress of the screw, so that they tend very stubbornly to resist back screwing. It is for the purpose of this action that I make the bolt so as to engage the rubber as a screw, thereby insuring its retention in place during the use of the shoe, the rubber thus substantially operating with the effect of a lock-nut. This effect may be greatly increased and rendered substantially positive by mutilating the thread 17, as seen at 20, so as to form upon one or more turns of the spiral a ratchet-like tooth sloping in direction to permit the screw to be advanced, but having its abrupt shoulder in the direction to resist reverse movement. This ratchet formation should not be sufficiently prominent to prevent the forcible retraction of the screw when a tool is applied to the head, but only to prevent it from working back when the shoe is in use.

The lugs 3 and 5 may be dispensed with by making the bolt long enough to extend through the whole length of the pocket and protrude its terminal 18 through the forward web of the skeleton or gridiron 4 and into the wall of the pocket at the forward end. This construction is illustrated in Fig. 4, the apertures 19 in the skeleton and 18 in the wall of the pocket being provided for this purpose. I have indicated the screw in this construction with the same numeral, 13, as the other, the only difference being in length.

I claim—

1. A horseshoe, comprising, in combination with a base adapted for fastening to the hoof and having on the under side pockets for heel-calks, calks for the same consisting each of a metal skeleton and a rubber body in which the skeleton is embedded, the skeleton being adapted to fit the pocket, and a bolt extending through the rear wall of the pocket and rear web of the skeleton and engaging

the skeleton and the base at a forward point, such bolt having a threaded portion, and one of the apertures through which it passes being correspondingly threaded for engagement therewith. 55

2. A horseshoe, comprising a metal base adapted to be fastened to the hoof and having pockets for heel-calks; calks for the same comprising each a metal skeleton and rubber body in which the skeleton is embedded, the skeleton being adapted to fit the pocket in the base, the rear wall of the pocket and the rear web of the skeleton being apertured to receive a retaining-bolt, and said skeleton and base having, respectively, at the forward point, parts contiguous at a transverse vertical plane apertured to receive such bolt, the bolt having a wood-screw thread engaging the rubber intermediate the rear and forward engagements of the bolt with the metal parts. 65

3. A horseshoe comprising a metal base and detachable heel-calks, the latter consisting of a metal skeleton embedded in a rubber body and bolts securing the calks to the base, having a portion which penetrates the rubber provided with a wood-screw thread, the thread being formed with ratchet-like irregularities 80 having abrupt shoulders facing in direction to resist retraction of the screw. 75

4. A horseshoe, comprising a metal base and detachable heel-calks lodged in pockets in the base, said calks consisting each of a metal skeleton and a rubber body in which the skeleton is embedded, the skeleton having a peripheral web which is contiguous to the wall of the pocket, a bolt for securing the calk to the base inserted through the pocket-wall and the contiguous web of the skeleton and having a threaded engagement with the latter and a wood-screw formation beyond such threaded engagement and being engaged with the rubber at the portion having such formation. 95

In testimony whereof I have hereunto set my hand, in the presence of two witnesses, at Chicago, Illinois, this 22d day of December, A. D. 1902.

FRED N. CLINE.
